[57] **CLAIM**

The ornamental design for a four-stripe side design for a shoe, as shown and described.

DESCRIPTION

FIG. 1 is a front perspective view of a four-stripe shoe side design showing my new design, the shoe shown in broken lines for illustrative purposes only and forms no part of the claimed design;

FIG. 2 is a top plane view thereof;

FIG. 3 is a left side elevational view thereof;

FIG. 4 is a right side elevational view thereof; and,

FIG. 5 is a front elevational view thereof.

The four-stripe side arrangement for a shoe of my new design is not seen in rear or bottom elevational views.
